UNITED STATES PATENT OFFICE.

MARK ANTHONY BROWN, OF SAVANNAH, GEORGIA, ASSIGNOR OF ONE-HALF TO D. G. PURSE, JR., OF SAVANNAH, GEORGIA.

CAR-COUPING.

No. 842,071.

Specification of Letters Patent.

Patented Jan. 22, 1907.

Application filed December 30, 1905. Serial No. 293,966.

To all whom it may concern:

Be it known that I, MARK ANTHONY BROWN, a citizen of the United States, residing at Savannah, in the county of Chatham and State 5 of Georgia, have invented a new and useful Improvement in Car-Couplers, of which the following is a specification.

This invention relates to an improvement in car-couplers, and especially to an automatic locking means applied to the car-coupler for which I filed application for Letters Patent July 24, 1905, Serial No. 271,066.

The object of this improvement is to provide means for locking the knuckle to the 15 coupler-head independent of the pivot-pin, thereby preventing the uncoupling of the cars in case the pivoted pin connecting the knuckle and coupler should break or become lost.

20 The invention consists of the novel features of construction hereinafter fully described, pointed out in the claims, and shown in the accompanying drawings, in which—

Figure 1 is a perspective view of my coupler, the parts being shown in an unlocked or open position. Fig. 2 is a front elevation of the coupler-head with the knuckle detached and shown in elevation adjacent the coupler. Fig. 3 is a horizontal section taken through 25 the coupler-head, knuckle, and a portion of the draw-bar, the knuckle being in open position. Fig. 4 is an elevation showing the inner face of the knuckle. Fig. 5 shows detail views illustrating portions of the knuckle 30 and coupler-head and showing the means to which this application especially relates, the upper view being an inverted perspective, showing a portion of the lower face of the knuckle and knuckle-arm and finger, and the 35 lower view being a perspective of the lower portion of one side of the coupler-head, a portion of the same being in section. Fig. 6 is a plan view illustrating diagrammatically the portion of the coupler-head shown in perspective in the lower part of Fig. 5 and showing the diagonal direction taken by a recess 40 formed in the coupler-head lug.

The general construction of this coupler is as a whole similar to that of the coupler 45 shown in my application for patent above referred to. It includes a hollow draw-bar A, a coupler-head A', and a detachable knuckle B. The coupler-head A' is provided with

parallel lugs A² in vertical alinement with each other and suitably perforated to receive 55 a pivoted pin A³ for the purpose of pivoting the knuckle B to the coupler-head.

The knuckle B comprises the vertically-arranged knuckle-head B', which carries an arm B³, which is recessed upon its inner face, 60 as shown at B⁴, and the arm B³ carries a finger B⁵ upon its inner face, which extends downwardly and inwardly and which is cut away adjacent its end upon the inner side to form a locking-shoulder B⁶. The knuckle-arm is also provided upon its upper and lower faces with vertical shoulders B⁷, which are wedge-shaped in cross-section and which terminate short of the knuckle-head B', thereby leaving a slight space between the 70 knuckle-head and the shoulders B⁷. The knuckle B above described is substantially the same as shown in my application above referred to, with the exception of the shoulder B⁶, formed on the knuckle-finger B⁵, and 75 the shoulders B⁷, formed upon the knuckle-arm B³, which features are new. To coöperate with these shoulders, a wedge-shaped shoulder is formed upon the inner face of that side or jaw of the coupler-head A' to 80 which the knuckle B is pivoted by the pin A³, and, as is clearly shown in Fig. 3, the shoulder B⁶ of the finger B⁵ engages the rear end of the shoulder A⁴ when the knuckle B is in a closed position. The opposing faces of the lugs A² 85 are recessed, as shown at A⁵, to receive the shoulders B⁷. The recesses A⁵ have curved walls A⁶, against which the shoulders B⁷ slide as the knuckle B swings from a closed to an open position. Both the outline of one of 90 these shoulders and the curved wall A⁶ of one of the recesses A⁵ are shown in dotted lines in Fig. 3.

It will be obvious from the drawings and the above description of construction that 95 when the knuckle is in a closed position the breaking of the pin A³ or its entire removal will not permit the knuckle to free itself, as it would be held in closed position by the engagement of the shoulders A⁴ and B⁶ and also by a locking-pin E, constructed and operating as described in the application for patent above referred to. When the locking-pin E is lifted by rotation of a rod I and the lifting of an arm I', to which the pin E is 100 connected by a suitable chain, the knuckle is 105

forced into an open position by a spring C, also described in my above-mentioned application, and while in such open position the knuckle B cannot be withdrawn even in the absence of the pin A³, except by an outward pull in a lateral direction by reason of the shoulders B⁷ being in engagement with the diagonally-extending recesses A⁵, the curvature of the recesses A⁵ and of the shoulders B⁷ being such that when the knuckle is in open position the shoulders B⁷ can be disengaged from the recesses only by a swinging or lateral movement of the knuckle and will not disengage by a direct pull. This locking effect is also increased by the wedge-shaped formation of the shoulders B⁷. The knuckle-head B' is also provided with a vertical perforation B², through which an ordinary coupling-pin may be run when a car having a coupler of this type is to be connected to a car provided only with one of the old pin-and-link type of couplers.

In Fig. 3 I have shown a horizontal section through the knuckle and head, showing the knuckle in its open position and showing the spring C having its free end portion bearing on the knuckle, and it will be noted that in this position the spring is slightly spaced from the adjacent wall of the coupler-head. It will be further noted that the tendency of this spring, which bears directly on the inner end portion of the arm B³ of the knuckle B, is to force the knuckle into a still further open position, which tendency is resisted and overcome by the shape of the knuckle, which will swing into open position only to the extent shown, the shoulders B⁷ locking in the recesses A⁵. As the knuckle cannot move inward to a closed position without forcing the spring C flat against the adjacent wall of the coupler-head, it will remain in open position until closed by force. It will also be obvious that any closing movement must be accompanied by a rotation of the knuckle on its pivot-pin, and during such rotation the spring C is in continual engagement with the knuckle and acts as a brake - band, thus

further insuring the knuckle against accidental closing by jars or the like.

Having thus fully described my invention, what I claim as new, and desire to secure by Letters Patent, is—

1. A coupler of the kind described comprising a coupling-head, lugs carried by said head in vertical alinement and recessed upon their opposing faces, a knuckle comprising a knuckle-head, a knuckle-arm, curved wedge-shaped shoulders formed on opposite sides of said arm and extending lengthwise thereof adapted to work in the recesses of the lugs, an outwardly-extending shoulder formed within the coupler-head, an outwardly and inwardly extending finger carried by the knuckle-arm and adapted to engage and lock with the shoulder of the coupling-head when the knuckle is in a closed position, and means for pivoting the knuckle to the coupler-head.

2. In a car-coupler, a coupler having an interior shoulder arranged upon one side, lugs arranged upon the same side and in vertical alinement, said lugs being perforated to receive a pivoted pin, recesses having curved end walls being formed upon the opposing faces of said lugs, a knuckle having an arm adapted to fit between said lugs, a pivoted pin passing through the lugs and arm, wedge-shaped shoulders formed on the upper and lower faces of the arm and adapted to move within the recesses of the lugs and to slide upon the curved walls of said recesses when the knuckle swings into open position, the outer faces of said shoulders being continuous with the outer face of the knuckle, and a finger downwardly and inwardly inclined carried by the inner faces of the knuckle-arm, said finger terminating in a shoulder adapted to engage the rear face of the shoulder formed in the coupler-head when the knuckle is in a closed position.

MARK ANTHONY BROWN.
